UNITED STATES PATENT OFFICE.

LESLIE I. ZIEGLER, OF INDIANAPOLIS, INDIANA, ASSIGNOR TO NORDYKE & MARMON COMPANY, OF INDIANAPOLIS, INDIANA, A CORPORATION OF INDIANA.

ELEVATOR.

1,306,509.

Specification of Letters Patent. Patented June 10, 1919.

Application filed April 20, 1918. Serial No. 229,663.

To all whom it may concern:

Be it known that I, LESLIE I. ZIEGLER, a citizen of the United States, residing at Indianapolis in the county of Marion and 5 State of Indiana, have invented a new and useful Elevator, of which the following is a specification.

My invention relates to elevators of the endless belt type, provided at intervals with 10 platforms onto and off of which persons may step or articles may be placed and removed at the different floors of a building, such as a factory.

It is the object of my invention to improve 15 and simplify the construction and mounting of the platforms of such elevators, whereby greater rigidity is insured and the chance of accident is minimized.

In attaining this object, I make each platform 20 a rigid structure with two clear unobstructed faces for use in ascent and descent respectively, and provide on each platform two pairs of spaced rollers for coöperating with guiding channel irons on each side of 25 the belt, so as to hold the platforms in proper position when under weight; and I connect each rigid double-faced platform with two cross bars attached to the endless belt, such connection to at least one of said 30 cross bars being by pin and slot connections permitting relative movement of such cross bar and platform as required when the distance between the two cross bars varies as the belt passes on to or off of the upper or 35 lower supporting pulley.

The accompanying drawing illustrates my invention. Figure 1 is a fragmentary front elevation of the elevator, with parts broken away; Fig. 2 is a side elevation of the elevator, also with parts broken away; Fig. 3 is an enlarged partial view of the endless belt and upper pulley, with one of the platforms passing around the pulley; and Fig. 4 is an enlarged section on the line 4—4 of 45 Fig. 2.

The endless carrying belt 10 travels over an upper pulley 11 and a lower pulley 12, mounted in suitable bearings and located above the top floor and below the lowest floor 50 between which the elevator is to carry per-

sons or articles. Suitable driving mechanism is provided for one of these pulleys—as shown, the upper pulley—the mechanism shown comprising a worm gearing 13 connecting the shaft 14 of the upper pulley 11 55 to a worm shaft 15 on which are fast and loose pulleys 16 whereby a controlled belt drive is obtained.

The belt 10 has fastened to it, as by bolts 20, a number of pairs of cross bars 21 and 22, 60 there being one pair of such cross bars for each double-faced platform with which it is desired to provide the belt. The two cross bars of each pair are spaced apart on the belt 10 by a definite distance; but the actual 65 distance between the two cross bars of a pair is less when the portion of the belt between them is on one of the pulleys 11 or 12 than it is when such belt portion is straight, and decreases and increases as such belt portion passes respectively on to and off of a pulley.

Associated with each pair of cross bars 21 and 22 is a double-faced platform 25, which is provided with two oppositely facing floor 75 plates 26 and 27 spaced apart and interconnected by two connecting frames 28 at opposite edges of the belt 10. These interconnecting frames are entirely between the two floor plates 26 and 27 except at the belt edges 80 of such floor plates, so that the working faces of such floor plates are entirely unobstructed, and in consequence the chance of accident is minimized. The two frames 28 are spaced apart by a distance slightly 85 greater than the width of the belt 10, as is clear from Fig. 4, so as to clear the edges of such belt. The frames 28 overlie the ends of the associated cross bars 21 and 22, and are connected to such cross bars so as to permit the varying of the distance between the cross bars without requiring any distortion of the platform. To this end the cross bar 21 is provided at its ends with pivot pins 29 which fit in pivot holes in one end of each 95 frame 28, at the belt line; and the cross bar 22 is provided at its ends with pivot pins 30 which project into slots 31 in the other end of each frame 28, at the belt line. The slots 31 may take different forms, but preferably 100

they are slightly oblique to the line connecting the pivot pins 29 and 30, as is clear from Fig. 3, as it is found in practice that this arrangement gives good results.

5 Each frame 28 is provided with two rollers 35, located at the two ends thereof substantially at the belt line and close to the cross bars 21 and 22. These rollers are guide rollers and travel in channel irons 36 located 10 at each edge of the belt 10 and properly shaped to conform to the line of travel of the rollers 35 as the belt 10 moves. At the top and bottom, where the belt 10 passes over the pulleys 11 and 12, the channel irons 15 36, if provided, are preferably slightly widened to allow a greater latitude of movement of the rollers 35; and at the lower pulley 12 the widening is greater than at the upper pulley 11 so as to allow for the 20 vertical adjustment of the shaft 37 of such lower pulley 12. The channel irons 36 co-operate with the rollers 35 to hold the platforms 25 in proper position, with the floor plates 26 and 27 thereof horizontal, as the 25 platforms are moving vertically between floors, so that such floor plates will be prevented from tilting from the horizontal by reason of the weight which is applied thereto. For additional safety, the belt is provided with hand grips 38.

In operation, the belt 10 is driven in the direction of the arrows, so that the platforms 25 travel up on one side, (the left in Fig. 2,) and down on the other side, (the 35 right in Fig. 2). The floor plate 27 of each platform is uppermost during the upward movement, while on the downward movement the floor plate 26 is uppermost. When a workman desires to travel from one floor 40 to another he steps on to the floor plate 27 of an ascending platform or the floor plate 26 of a descending platform as such platform passes the floor he is on, holding himself steady by the hand grip 38, and steps 45 off when he reaches the floor where he desires to be. Similarly, any articles which it is desired to move upward or downward are placed on the floor plates of the platforms as they pass one floor and taken off 50 as they pass another. The rigid construction of the entire platform makes for stability and safety, as well as for simplicity in construction; while the pin and slot connection 30—31 provided for the necessary variation in the distance between the cross bars 21 and 22.

I claim as my invention:

1. In an endless belt elevator, the combination with the endless carrier, of a pair 60 of cross bars mounted on said endless carrier, a rigid double-faced platform mounted on said pair of cross bars and having a pin and slot connection with one of such

cross bars, said platform having two opposite platform faces fixed relatively to each other and facing respectively forward and rearward with respect to said endless carrier, guide rollers carried by said platform, and channel irons in which said guide rollers of travel.

2. In an endless belt elevator, the combination with the endless carrier, of a pair of cross bars mounted on said endless carrier, and a rigid double-faced platform mounted on said pair of cross bars and having a pin and slot connection with one of such cross bars, said platform having two opposite platform faces fixed relatively to each other and facing respectively forward and rearward with respect to said endless carrier.

3. In an endless belt elevator, the combination with the endless carrier, of a pair of cross bars mounted on said endless carrier, a rigid double-faced platform comprising two oppositely facing floor plates connected by rigid frames at the edges of said endless carrier so that such plates are fixed relatively to each other and face respectively forward and rearward along said endless carrier, said frames being pivotally connected at one end to the ends of one of said cross bars and at the other end having pin and slot connections with the ends of the other cross bar, a pair of spaced guide rollers carried by each of said frames, and channel irons with which said guide rollers co-operate.

4. In an endless belt elevator, the combination with the endless carrier, of a pair of cross bars mounted on said endless carrier, and a rigid double-faced platform comprising two oppositely facing floor plates connected by rigid frames at the edges of said endless carrier so that such plates are fixed relatively to each other and face respectively forward and rearward along said endless carrier, said frames being pivotally connected at one end to the ends of one of said cross bars and at the other end having pin and slot connections with the ends of the other cross bar.

5. In an endless belt elevator, the combination with the endless carrier, of a pair of cross bars mounted on said endless carrier, a rigid double-faced platform comprising two oppositely facing floor plates connected by rigid frames at the edges of said endless carrier, said frames being pivotally connected at one end to the ends of one of said cross bars and at the other end having obliquely extending slots which receive the ends of the other cross bar, a pair of spaced guide rollers carried by each of said frames, and channel irons with which said guide rollers co-operate.

6. In an endless belt elevator, the com-

bination with the endless carrier, of a pair of cross bars mounted on said endless carrier, and a rigid double-faced platform comprising two oppositely facing floor plates 5 connected by rigid frames at the edges of said endless carrier, said frames being pivotally connected at one end to the ends of one of said cross bars and at the other end hav-

ing obliquely extending slots which receive the ends of the other cross bar. 10

In witness whereof I have hereunto set my hand at Indianapolis, Indiana, this 18th day of April, A. D. one thousand nine hundred and eighteen.

LESLIE I. ZIEGLER.
